UNITED STATES PATENT OFFICE.

EKINS HAND, OF ROCHESTER, NEW YORK, ASSIGNOR OF TWO-THIRDS TO
PETER E. RIVARD AND GEORGE A. SABEY, BOTH OF SAME PLACE.

HYDRANT.

SPECIFICATION forming part of Letters Patent No. 377,357, dated January 31, 1888.

Application filed September 12, 1887. Serial No. 249,512. (No model.)

To all whom it may concern:

Be it known that I, EKINS HAND, of Rochester, in the county of Monroe and State of New York, have invented a certain new and useful Improvement in Hydrants; and I do hereby declare that the following is a full, clear, and exact description of the same, reference being had to the drawings accompanying this application.

10 The object of my invention is to prevent water from standing in the hydrant when the supply is turned off, and the consequent freezing of the same in cold weather.

To this end my invention consists in the construction and arrangement of the lower part 15 of the hydrant, as hereinafter more fully described and definitely claimed.

In the drawings, Figure 1 is a central vertical section of the lower portion of the hydrant. 20 Fig. 2 is a cross-section of the same in line $x x$ of Fig. 1. Fig. 3 is an end view of the cut-off piston. Fig. 4 is a view of the screw-guide.

My improvement relates, particularly, to the lower end of the hydrant, where water is admitted from the main and where the waste 25 water is discharged.

A indicates the casing, provided with a nozzle, B, through which the induction water is admitted from the main.

30 C is the cut-off piston or plunger for controlling the admission of the water. It consists of a circular head, a, provided with a packing, b, that fits a seat at the inner end of the nozzle, and legs c c, that rest in the nozzle 35 and form guides, and a stem, d, extending back across the inside of the casing, as shown in the drawings.

G is a screw passing in through the back of the casing, its inner end being smooth and 40 passing into a hole in the end of the stem d, and serving as a guide to hold the piston in place as it moves forward and backward.

E is a rod or bar extending down vertically 45 through the hydrant, passing through a slot, f, in the piston-stem d, and provided above the slot with a wedge-shaped lug, h. When the rod is forced down, the wedge-shaped lug will force the piston out, so as to seat it against the nozzle B, and thus cut off the flow of water. 50 When it is raised again, the piston will open

to allow the water to flow. The end of the screw G passes into the slot f of the piston-stem d and serves as the backing or fulcrum for the rod to act against. By turning said screw up or back more or less, the throw of 55 the piston will be correspondingly changed.

It will be seen that the screw performs the double purpose of a fulcrum for the operating-rod and a guide and support for the piston, which slides freely thereon. The legs c c, 60 reaching into the nozzle, serve as guides to the front end of the piston.

H is a valve at the bottom of the hydrant to discharge the waste water. It strikes upward against a seat, m, to cut off the flow and 65 opens downward to discharge the waste.

r is a stem of the valve, that passes down through a bearing, p, and s is a spiral spring around the stem for throwing the valve up.

l is a collar containing the valve, said collar 70 screwing on a nozzle, k, at the bottom of the hydrant, and having a thread at its lower end, on which screws the discharge-pipe. The upper end of valve H extends above the bottom of the hydrant, as shown in Fig. 1, and 75 the rod or bar E projects below the piston, and these parts are so relatively arranged that when the rod E is forced down sufficiently to close the piston C and cut off the ingress of water from the main the lower end of said 80 rod strikes the valve H and opens it, so as to discharge the waste water in the hydrant. By this means the hydrant is always kept free of waste water when the flow from the main is cut off. 85

Having described my invention, what I claim as new, and desire to secure by Letters Patent, is—

1. In a hydrant, the combination, with the casing provided with an induction-opening, 90 of the piston C, provided with head a and slot f, the rod E, provided with wedge-shaped lug h, passing through the slot of the piston-stem, and the supporting and adjusting screw G, on which the piston slides, as herein shown and 95 described.

2. In a hydrant, the combination, with the casing provided with an induction-opening, 100 of the piston C, provided with head a and slot f, the rod E, provided with wedge-shaped lug

h, passing through the slot of the piston-stem, the adjusting-screw *G*, on which the piston slides, the valve *H*, located in the bottom of the hydrant below the rod, and the spring *s*, closing the valve in its seat, as shown and described, and for the purpose specified.

In witness whereof I have hereunto signed

my name in the presence of two subscribing witnesses.

EKINS HAND.
